US0D1000189S

(12) United States Design Patent (10) Patent No.: US D1,000,189 S
(45) Date of Patent:  Oct. 3, 2023

(54) BARBECUE TOOLSET

(71) Applicant: Huizhou Haorui Hardware Technology Co., Ltd, Huizhou (CN)

(72) Inventors: Yong Zhang, Huizhou (CN); Chaosen Wang, Huizhou (CN)

(73) Assignee: Huizhou Haorui Hardware Technology Co., Ltd, Huizhou (CN)

() Term: 15 Years

(21) Appl. No.: 35/515,175

(22) Filed: Sep. 9, 2022

(80) Hague Agreement Data

Int. Filing Date: Sep. 9, 2022

Int. Reg. No.: DM/223350

Int. Reg. Date: Sep. 9, 2022

Int. Reg. Pub. Date: Sep. 23, 2022

(51) LOC (14) Cl. 07-02

(52) U.S. Cl.

USPC D7/334

(58) Field of Classification Search

USPC D7/337-339, 341

CPC A47J 37/06; A47J 37/00; A47J 33/00

See application file for complete search history.
